UNITED STATES PATENT OFFICE.

FRANK A. ROBINSON, OF BROOKLYN, NEW YORK, ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,202,070.

Specification of Letters Patent. Patented Jan. 21, 1910.

Application filed July 10, 1913. Serial No. 773,246.

To all whom it may concern:

Be it known that I, FRANK A. ROBINSON, a citizen of the United States, residing in Brooklyn borough, in the county of Kings, 5 city and State of New York, have invented certain new and useful Improvements in Combined Type-Writing and Computing Machines, of which the following is a specification.

10 This invention relates to computing machines, particularly to those which are combined with typewriting machines, and is illustrated in connection with combined typewriting and computing machines of the 15 Underwood-Wright type.

Heretofore in performing the operation of grand totalizing in these machines, it has been customary to mount the grand totalizer in such a manner as to necessitate the provision of a separate master wheel shaft therefor, especially where it was desired to use a sub-totalizer which was adapted for cross-computation.

20 The principal object of the present improvements is to simplify the construction and operation of the machine; and to this end both the sub-totalizer and the grand totalizer are arranged upon a single computing carriage, which is usually connected to 25 travel with the typewriter carriage; and a single master wheel shaft is made to answer for both totalizers; while a single assisting shaft answers for assisting the tens-carrying operation in both totalizers.

30 Several master wheels are placed at intervals along the master wheel shaft, and the sub-totalizer and the grand totalizer are so arranged in respect to these master wheels, that at the initial operation the same number is added in both totalizers; and during 35 subsequent operations the grand totalizer remains unaffected, while a second number may, if desired, be added in the sub-totalizer. Finally the sub-totalizer may be cleared by 40 setting the master wheel shaft to subtraction, and operating the keys to write upon the work-sheet the number that appears in the sub-totalizer; whereby the latter is returned to zero, while the grand totalizer 45 accumulates only the amounts of the items that are inserted in the sub-totalizer.

While the invention is useful for a great variety of purposes, it is shown especially arranged for making out bills for telephone 50 bills. The arrangement and number of mas-

ter wheels on the master wheel shaft may however be varied; and other variations may be resorted to within the scope of the invention, for different purposes.

Other features and advantages will hereinafter appear.

In the accompanying drawings,

Figure 1 is a perspective view of the upper front portion of an Underwood-Wright combined typewriting and computing machine, showing the present improvements, and enough of a computing machine to show how they are connected thereto.

Fig. 2 is a diagrammatic front view to illustrate the manner of adding an item on both the sub-totalizer and the grand totalizer.

Fig. 3 is a view to show the addition on the sub-totalizer of an amount equal to the previous balance which appears on the work-sheet; the grand totalizer at this time being silenced.

Fig. 4 is a view similar to Fig. 3, but illustrating the manner of subtracting from the sub-totalizer (as for instance in returning it to zero) without disturbing the grand totalizer.

Fig. 5 illustrates the usual key-controlled mechanism for setting the machine to either addition, subtraction or neutral.

Fig. 6 is a sectional side elevation taken through one of the totalizers seen in Fig. 1.

Fig. 7 is a diagram similar to Fig. 2, but showing a form of the invention by which cross-adding can be done on the sub-totalizer and the amount thereof accumulated on the grand totalizer, and other operations performed. In this figure, as well as Figs. 2, 3 and 4, the illustration of the gears 21, 22 and 23 is diagrammatic to indicate which gear 23 is driving. The gears themselves are not actually moving but the clutch shifted as in Fig. 5.

In adapting the machine for a particular style of work, I employ a temporary or sub-totalizer 1 and a permanent, main or grand totalizer 2, and four master wheels, 3, 4, 5 and 6; the master wheel 6 being used for the main totalizer, the master wheel 5 for the sub-totalizer, the master wheel 4 for bringing forward the previous sub-total, and the master wheel 3 for clearing the sub-totalizer; said master wheels fixed on the horizontal shaft 7, and said totalizers secured by clamps 8 upon a carriage 9 which

is connected to the typewriter carriage 10 by means of a lug 11 mounted on the typewriter carriage and engaging a rack 12 on the computing carriage.

5 For convenience the machine is illustrated as adapted to make out bills 13 for telephone tolls, the bill being placed around the platen 14 of the typewriter, and the amounts being written thereon by depressing the usual numeral keys to throw the types against the platen.

The bill 13 is so placed in the machine, and the computing carriage 9 is so adjusted with relation to the typewriter carriage 10, 15 that when the operator shifts the typewriter carriage 10 to position for writing in the first column 15 on the bill, the totalizers 1, 2 are in position to be operated by the two right-hand master wheels 5, 6. The writing 20 proceeds line by line in the usual manner, and after the first three lines are written on the bill, each of these totalizers shows "30." The operator then shifts the carriages together until the temporary or sub-totalizer 1 25 is engaged by the master wheel 3, and also manipulates a key 16 to set the machine for subtraction. At this time the last column on the sheet is at the printing point, and the operator writes on said column the amount 30 seen on the sub-totalizer 1, namely, "30." At the same time this number is subtracted from the sub-totalizer 1, the number being, however, left in the permanent or grand 35 totalizer 2.

35 The operator then removes the bill from the machine and inserts another bill and proceeds in the same manner, the total of the charges being printed in the right-hand column of said bill, and the sub-totalizer 1 40 finally showing "0," while the grand totalizer 2 now shows the total of the two bills. In like manner the operator proceeds to write all of the bills for the day.

On the second and each succeeding day of 45 the month, each bill is again inserted by the operator into the machine, and new items are added as before. Fig. 2 shows the totalizers after the first bill has been written on the second day. The items on this bill 50 amount to twenty-five cents, and hence each totalizer shows "25." The operator now shifts the typewriter and computing carriages over until the sub-totalizer 1 registers with the carry-forward master wheel 4, and 55 at this time adds on the sub-totalizer the total of the previous day's charges, which in this instance is thirty cents, so that the sub-totalizer now reads "55," as at Fig. 3. During this work, the grand totalizer 2 is out 60 of range of any master wheel, and hence retains the amount "25." The amount "30" is written on the work-sheet 13 in the special column 17 which may be headed "Old balance." The operator then shifts the car- 65 riages for the Fig. 4 position, and operates

the key 16 to set the machine for subtraction, and then writes in column 18 the amount which shows on the sub-totalizer 1, namely, "55;" this column 18 being headed "New balance." Of course, after each operation 70 of the clearing wheel 3 the operator restores the key 16 to set the machine back for addition.

75 It will be understood that when the parts are in the Fig. 4 position, and the sub-totalizer is engaged by the clearance master wheel 3, the grand totalizer is clear of any master wheel and retains the amount therein. The grand totalizer, in fact, is not engaged by any master wheel except the grand master 80 wheel 6; whereas the sub-totalizer engages successively the sub-totalizing master wheel 5, the carry-forward master wheel 4 and the clearing master wheel 3.

85 One of the advantages of the improvements is that both sub-totalizing and grand totalizing can be performed, and the sub-totalizer also cleared, all by the use of a single adding carriage and a single master wheel shaft. This simplifies the construction and operation of this class of machines, and the invention is also particularly valuable where it is desired to bring forward a prior balance by adding the same in the sub-totalizer without adding it in the grand 95 totalizer.

The master wheel shaft is power-rotated, and is controlled by means of the type-operated keys of the typewriter, in the manner illustrated in the application of Gustave 100 Dégener, No. 753,254, filed March 10, 1913 (now Patent No. 1,261,107). As disclosed in said application, the master wheel shaft is rotated by a power-driven shaft 19, which has a reversible connection with master 105 wheel shaft 7 (Figs. 1 and 5), comprising a clutch 20 splined to shaft 19 and shiftable up and down by the finger key 16, to connect the shaft 19 with either the lower bevel pinion 21 or the upper bevel pinion 22, thus 110 reversibly driving the pinion 23 on the master wheel shaft 7.

115 As set forth in said application, each of the totalizers comprises a series of computation wheels 24 having internal teeth to be engaged by the master wheel, and having also external teeth meshing with gears 25 on the number wheels 26.

The tens-carrying mechanism, as set forth in said application, includes a special tooth 120 27 on each computation wheel 24, and once in each revolution this tooth engages and turns a five-toothed wheel 28, which forms one of a set of three rigidly connected wheels, the others being numbered 29 and 125 30. The wheel 29 is turned far enough to enable one of its toothed points 31 to engage a constantly revolving pinion 32, which serves as a prime mover to complete the tens-carrying operation; said pinion 32 driving 130

not only the wheel 29, but also the pinion 30 which is in mesh with the computation wheel 24 of next higher denomination.

The pinion 32 is of the elongated or barrel variety, so as to be effective during the entire travel of the totalizer 2 past the master wheel 6. This pinion 32 is fixed on a shaft 33, which, as shown in said application, is connected to a power-driven drive shaft 34 by means of pinions 35, 36, 37, 38 and 39, the last two being mounted on shaft 34 and having a shiftable reversing clutch 40, connected to the finger key 16, so that, when the master wheel shaft 7 is reversed, the tens-carrying pinion 32 is reversed accordingly.

It will be seen that, according to the present improvements, the shaft 33 is prolonged past the elongated pinion 32, and is provided with additional pinions 41, 42 and 43, for the additional master wheels 5, 4 and 3, respectively. It will be seen that the machine is greatly simplified, as compared with a machine in which a separate master wheel and a separate tens-carrying shaft must be provided for a reciprocating grand totalizer; both sub-totalizer and grand totalizer being herein shown on one carriage, and the master wheels being fixed on one shaft, and the tens-carrying pinions for the four master wheels being also fixed on one shaft.

As set forth in said application, detent rolls 44 are carried on arms 45 pivoted at 46, and springs 47 press the rolls into notches formed in the wheel 29 of each tens-carrying train; and in order to relieve the obstruction to the turning of the wheels, each detent roll is automatically released during the wheel-rotating operation; this release being effected by a pin 48, which is projected by an arm 49, as at Fig. 6, to carry the roll 44 away from the wheel 29. At the same time the lower end of the arm 45, which is prism-shaped or beveled, as seen at Fig. 1, is forced into a notch or seat in a locking device 50 provided upon a bar 51 which forms a part of the machine frame. This locks the adding machine carriage firmly during the rotation of the adding wheels.

The arm 49 is on a rock shaft 52 which extends parallel with shaft 33, and carries on one end an arm 53, which is connected by a link 54 to the upper end of a rod 55, which is lifted by a spring 56 at the operation of a numeral key, as set forth in said application. This spring 56 also actuates, through the rod 55, other mechanism essential for a computing operation, indicated in general at 57.

It will be seen at Fig. 1 that according to the preferred form of the present improvements, there are provided additional locks 58, 59 and 60, to cooperate with the arms 45 of the sub-totalizer; the shaft 52 being provided with four arms 49, to operate the pins 48.

Reference is also made to Degener application No. 775,621, filed June 23, 1913, and also to Degener Patents Nos. 1,163,644, dated December 14, 1915, and 1,260,759, dated March 26, 1918.

Referring to Fig. 7, the master wheel shaft carries an extra master wheel 61, for cross-adding; this master wheel working on the grand totalizer 2 at the same time the master wheel 4^a (occupying the same position on said shaft as the master wheel 4 at Fig. 3 and having associated with it a pinion 42^a) is acting on the sub-totalizer. In other words, the amounts inserted or added in the sub-totalizer 1 by the master wheels 5 and 4^a, during the writing of two numbers (in different columns) in the same line of writing, are at the same time accumulated in the grand totalizer 2. Then the master wheel 5 at Fig. 7 may, if desired, be employed to return the sub-totalizer 1 to zero, without disturbing the amount in the grand totalizer 2. Thus cross-addition may be performed by two totalizers arranged on the same carriage and coöperating with four master wheels on the same shaft; and by means of a fifth master wheel subtraction may also be performed on the sub-totalizer, without disturbing the grand totalizer.

Associated with the grand cross totaling master wheel 61 is a pinion 62 fixed on the same shaft 33 with the pinions 32, 41, 42^a and 43; and it will be understood that an additional locking member 63 may be employed, as well as additional setting members at this point to correspond with the setting members 49 and 48, said additional members to be fixed on the same rock shaft 52.

Variations may be resorted to within the scope of the invention, and portions of the improvements may be used without others.

Having thus described my invention, I claim:

1. The combination with a shaft, of a series of master wheels thereon, totalizer mechanisms less in number than the number of master wheels and operable by said master wheels, and power-driven mechanism for assisting the tens-carrying operation, including a power-driven shaft having a pinion individual to each of said master wheels and correlated solely therewith.

2. The combination with a carriage and totalizers thereon, of a shaft having master wheels to operate said totalizers, each totalizer having locking arms, and means correlated with each master wheel to coöperate with said arms to lock the totalizer during the computation operation, said locking means comprising a series of locking seats, a series of pins opposite said seats for moving the totalizer arms into the seats, and a single shaft having means for simultaneously operating all of said pins.

- 4.
3. The combination with a typewriter carriage, of a computing carriage connected thereto, a sub-totalizer, a grand totalizer, a shaft having master wheels, including a 5 grand master wheel, a sub-totalizing master wheel, and a master wheel for returning the sub-totalizer to zero, said computing carriage being connected to effect relative movements between the master wheels and 10 the totalizers; the master wheels and totalizers being so disposed that the grand master wheel and the sub-totalizing master wheel are active simultaneously upon the totalizers, so that the grand totalizer is out 15 of range of any master wheel when the third master wheel is active upon the sub-totalizer for returning the same to zero, and an assisting power shaft extending along said master wheel shaft and having adjacent to 20 the master wheels means for assisting at the tens-carrying operations of the several totalizers.
4. The combination with a typewriter carriage, of a computing carriage connected thereto, a sub-totalizer, a grand totalizer, a shaft having master wheels, including a 25 grand master wheel, a sub-totalizing master wheel, and a master wheel for returning the sub-totalizer to zero, said computing carriage being connected to effect relative movements between the master wheels and 30 the totalizers; the master wheels and totalizers being so disposed that the grand master wheel and the sub-totalizing master wheel are active simultaneously upon the totalizers, so that the grand totalizer is out of range 35 of any master wheel when the third and fourth master wheels are active upon the sub-totalizer for returning the same to zero, and an assisting power shaft extending along said master wheel shaft and having adjacent to 40 the master wheels means for assisting at the tens-carrying operations of the several totalizers, each totalizer including computation wheels and locking means therefor, and means coöperative with each totalizer at 45 each operation thereof for releasing the locking means.
5. The combination with a typewriter carriage, of a computing carriage connected thereto, a sub-totalizer, a grand totalizer, a shaft having master wheels, including a 50 grand master wheel, a sub-totalizing master wheel, and a master wheel for returning the sub-totalizer to zero, said computing carriage being connected to effect relative movements between the master wheels and 55 the totalizers; the master wheels and totalizers being so disposed that the grand master wheel and the sub-totalizing master wheel are active simultaneously upon the totalizers, so that the grand totalizer is out of range 60 of any master wheel when the third master wheel is active upon the sub-totalizer for returning the same to zero, and an assisting power shaft extending along said master wheel shaft and having adjacent to the master wheels means for assisting at the tens-carrying operations of the several totalizers, each totalizer including computation wheels and locking means therefor, and means coöperative with each totalizer at each operation thereof for releasing the locking means.
6. In a combined typewriting and computing machine, the combination with a typewriter carriage, of a computing carriage connected thereto, a sub-totalizer and a 65 grand totalizer secured upon said computing carriage, and a master wheel shaft mounted upon the machine frame and having a grand master wheel, a sub-totalizing master wheel, a master wheel for returning the sub-totalizer to zero, and a fourth master wheel for adding an amount upon the sub-totalizer independently of the grand totalizer, the master wheels and totalizers being so disposed that the grand master 70 wheel and the sub-totalizing master wheel are active simultaneously upon the totalizers, so that the grand totalizer is out of range of any master wheel when the third and fourth master wheels are active upon the 75 sub-totalizer.
7. The combination, with a carriage; of a sub-cross-totalizer and a grand totalizer thereon, said totalizers having fixed relation to each other during the operation 80 thereof; and means for operating said totalizers in a cycle, said cycle operating means including a master wheel individual to each of said totalizers for operating the same, and master wheels separate from and additional to the first-named master wheels and so disposed with relation to said totalizers as to be capable of operating solely one totalizer, during the cycle of operation of 85 said totalizers.
8. The combination with a carriage, of a sub-cross totalizer and a grand totalizer thereon, said totalizers having fixed relation to each other during the operation 90 thereof, master wheels for operating said totalizers, additional master wheels for operating a part only of said totalizers, and reversing means for restoring the sub-cross totalizer to zero at the operation of writing the number that appears on the sub-cross 95 totalizer, without disturbing the grand totalizer.
9. The combination with a totalizer movable to different predetermined positions, said totalizer comprising computation wheels and detents therefor, of means at each of such positions for performing different computations on said totalizer, each computa- 100
- 105
- 110
- 115
- 120
- 125

tion equal to the capacity of the totalizer, and means at each position for locking the totalizer against being shifted and for releasing the totalizer detents one-by-one.

10. In a computing machine, the combination with a computing carriage, of a sub-totalizer and a grand totalizer upon said carriage, a master wheel shaft on the machine frame having two master wheels for the grand totalizer and also having two master wheels for the sub-totalizer, whereby cross-footing may be performed simultaneously upon the grand totalizer and upon the sub-totalizer, an additional master wheel 15 upon said shaft for returning the sub-totalizer to zero, means to reverse the direction of operation of the master wheel shaft, and an assisting power shaft extending along said master wheel shaft and having adjacent to the master wheels means for assisting at the tens-carrying operations of the several totalizers.

11. In a computing machine, the combination with a computing carriage, of a sub-totalizer and a grand totalizer upon said carriage, a master wheel shaft on the machine frame having two master wheels for the grand totalizer and also having two master wheels for the sub-totalizer, whereby cross-footing may be performed simultaneously upon the grand totalizer and upon the sub-totalizer, an additional master wheel upon said shaft for returning the sub-totalizer to zero, means to reverse the direction of operation of the master wheel shaft, an assisting power shaft extending along said master wheel shaft and having adjacent to the master wheels means for assisting at the tens-carrying operations of the several totalizers; each totalizer including computation wheels and locking means therefor, and means co-operative with each totalizer at each operation thereof for releasing the locking means.

12. In a computing machine, the combination with a computing carriage, of a sub-totalizer and a grand totalizer upon said carriage, a master wheel shaft on the machine frame having two master wheels for the grand totalizer and also having two master wheels for the sub-totalizer, whereby cross-footing may be performed simultaneously upon the grand totalizer and upon the sub-totalizer, an additional master wheel upon said shaft for returning the sub-totalizer to zero, means to reverse the direction of operation of the master wheel shaft, an assisting power shaft extending along said master wheel shaft and having adjacent to the master wheels means for assisting at the tens-carrying operations of the several totalizers; each totalizer including computation wheels and locking means therefor, and means co-operative with each totalizer at each

operation therefor for releasing the locking means, and for simultaneously locking the totalizers against displacement during the computation operations.

13. The combination with a plurality of totalizers, of a plurality of irregularly spaced master wheels of greater number than the number of said totalizers for driving said totalizers, and traversing means for effecting a relative movement between said totalizers and said master wheels so as to enable the driving action of different ones of said master wheels.

14. The combination with a plurality of totalizers, of a plurality of irregularly spaced master wheels of greater number than the number of said totalizers for driving said totalizers, traversing means for effecting a relative movement between said totalizers and said master wheels so as to enable the driving action of different ones of said master wheels, and shifting means for varying the character of drive of said master wheels, and hence the character of computation run up in said totalizers.

15. The combination with a plurality of totalizers moving always in a single rectilinear path, of a plurality of irregularly spaced master wheels controlling the periods of activity of said totalizers, and traversing means for moving said totalizers to bring the same into or out of the sphere of action of the proper master wheel, the relative spacing of said master wheels to said totalizers determining the asynchronal or synchronal activity of the totalizers.

16. The combination with a plurality of totalizers, of a plurality of master wheels for driving said totalizers, the number of master wheels being greater than the number of said totalizers, said master wheels being arranged in groups of one or more, one group being spaced from another group a distance at least as great as the aggregate spacing of the master wheels in the latter group.

17. The combination with a typewriter carriage, of a computing carriage adjustable relatively to said typewriter carriage, a plurality of totalizers mounted on said computing carriage so as to be adjusted in unison relatively to said typewriter carriage, a single master wheel shaft, and a plurality of allotted groups of master wheels on said shaft, the relative grouping of said master wheels to said totalizers serving, during the travel of said carriages, to determine the asynchronal and synchronal activity of said totalizers.

18. The combination with a plurality of totalizers, of a plurality of master wheels, and traversing means for moving said totalizers in a rectilinear direction to co-operate with said master wheels so as to be driven

thereby, said totalizers being always driven when in the zone of a master wheel, the positioning and travel of said totalizers and the spacing of said master wheels being so related that part will be acting while part is inactive, due solely to the relative registration of the totalizers with the master wheels.

19. The combination, with a pair of separate totalizers having fixed positions relative to one another during a cycle of operation thereof; of a master wheel co-acting with solely one of said totalizers during said cycle; a plurality of additional master wheels all selectively co-acting with solely 15 the other totalizer during said cycle; and a common shaft whereon all of said master wheels are mounted; said totalizers and said shaft having a relative traveling movement between them, such that the first-named master wheel is thereby brought out of co-action 20 with the first-named totalizer, and a selected second-named master wheel simultaneously brought into co-action with the second-named totalizer.
20. The combination, with a pair of separate totalizers having fixed positions relative to one another during a cycle of operations thereof; of a master wheel co-acting with solely one of said totalizers during said 25 cycle; a plurality of additional master wheels all selectively co-acting with solely the other totalizer during said cycle; and a common support for all of said master wheels; said totalizers and said support having a relative traveling movement between them, such that the first-named master wheel is thereby brought out of co-action with the first-named totalizer, and the second-named master wheels successively brought into co-30 action with the second-named totalizer.
21. The combination, with a pair of separate totalizers having fixed positions relative to one another during a cycle of operation thereof; of a pair of master wheels, one individual to each totalizer and normally connected therewith, for operating said totalizers simultaneously; a plurality of master wheels separate from, and additional to, the first-named master wheels, selectively 35 operative upon solely one predetermined totalizer during said cycle; and a shaft whereon all of said master wheels are mounted; said totalizers and said shaft having a relative traveling movement between them, such that the first-named master wheels are thereby disconnected simultaneously from their respective totalizers, and a selected one of the additional master wheels connected with said predetermined totalizer substantially 40 concurrently with the disconnection of said first-named master wheels.

22. The combination, with a pair of separate totalizers having fixed positions relative to one another during a cycle of opera-

tion thereof; of a pair of master wheels, 65 one individual to each totalizer and normally connected therewith, for operating said totalizers simultaneously; a plurality of master wheels separate from, and additional to, the first-named master wheels, 70 selectively operative upon solely one predetermined totalizer during said cycle; a common support for all of said master wheels; and a carriage providing a relative traveling movement between said totalizers and 75 said support, such that, during a single run of the carriage, both first-named master wheels will be thereby disconnected simultaneously from their respective totalizers, and the additional master wheels successively connected, one after another, with said predetermined totalizer, the other totalizer remaining inactive throughout the period of activity of the additional master wheels.

23. The combination, with a pair of separate totalizers having fixed positions relative to one another during a cycle of operation thereof; of a master wheel co-acting with solely one of said totalizers during said cycle; a plurality of additional master wheels all selectively co-acting with solely the other totalizers during said cycle; a common shaft whereon all of said master wheels are mounted; said totalizers and said shaft having a relative traveling movement 95 between them, such that the first-named master wheel is thereby brought out of co-action with the first-named totalizer, and a selected second-named master wheel simultaneously brought into co-action with the second-named totalizer; and a power-driven mechanism for assisting the tens-carrying operation, comprising a power-driven shaft having thereon a pinion individual to each of said master wheels and correlated 105 solely therewith.

24. The combination, with a pair of separate totalizers having fixed positions relative to one another during a cycle of operation thereof; of a denomination-determining member controlling computation in solely one of said totalizers during said cycle; and a plurality of additional denomination-determining members all selectively controlling computation in solely the other totalizers during said cycle; said totalizers and said denomination-determining members having a relative traveling movement between them, such that the first-named determining member is thereby 115 brought out of co-action with the first-named totalizer, and a selected second-named determining member simultaneously brought into co-action with the second-named totalizer.

25. The combination, with a pair of separate totalizers having fixed positions relative to one another during a cycle of opera-

tion thereof; of a denomination-determining member controlling computation in solely one of said totalizers during said cycle; and a plurality of additional determining members all selectively controlling computation in solely the other totalizer during said cycle; said totalizers and said denomination-determining members having a relative traveling movement between them, such that the first-named determining member is thereby brought out of co-action with the first-named totalizer, and the second-named determining members successively brought into co-action with the second-named totalizer.

26. The combination, with a pair of separate totalizers having fixed positions relative to one another during a cycle of operation thereof; of a pair of denomination-determining members, one individual to each totalizer, for controlling computation therein, said determining members being normally ineffective position with relation to said totalizers; and a plurality of denomination-determining members separate from, and additional to, the first-named determining members, for selectively controlling computation in solely one predetermined totalizer during said cycle; said totalizers and said denomination-determining members having a relative traveling movement between them, such that the first-named determining members are thereby brought simultaneously into ineffective position with relation to their respective totalizers, and a selected one of the additional determining members brought into effective position with relation

to said predetermined totalizer substantially concurrently with the rendering of said first-named determining members ineffective.

27. The combination, with a pair of separate totalizers having fixed positions relative to one another during a cycle of operation thereof; of a pair of denomination-determining members, one individual to each totalizer, for controlling computation therein, said determining members being normally in effective position with relation to said totalizers; and a plurality of denomination-determining members separate from, and additional to, the first-named determining members, for selectively controlling computation in solely one predetermined totalizer during said cycle; said totalizers and said denomination-determining members having a relative traveling movement between them, such that both first-named determining members are thereby brought simultaneously into ineffective position with relation to their respective totalizers, and the additional determining members successively brought into effective position, one after another, with relation to said predetermined totalizer, the other totalizer having its individual determining member remaining ineffective with relation thereto throughout the entire period of effectiveness of said additional determining members.

FRANK A. ROBINSON.
